COMBINED BOTTLE AND CAP

Jerome Gould, Encino, Calif., assignor to "42" Products, Ltd., Inc., Santa Monica, Calif., a corporation of California

Filed Feb. 7, 1966, Ser. No. 942

Term of patent 14 years

(Cl. D58—8)

FIG. 1.

FIG. 2.

FIG. 3.

FIGURE 2 is a side elevational view, the opposite side being the same in appearance; and

I claim:

The ornamental design for a combined bottle and cap, substantially as shown and described.
